CLAIM

The ornamental design for a shoe, as shown and described.

DESCRIPTION

FIG. 1 is a lateral side view of an embodiment of a shoe, it being understood that there is no claim being made to the bottom features, other than those visible in the views of the drawing disclosure for this embodiment, therefore the bottom view of this embodiment has been omitted.

FIG. 2 is a medial side view of the shoe of FIG. 1.

FIG. 3 is a top lateral rear perspective view of the shoe of FIG. 1.

FIG. 4 is a top medial front perspective view of the shoe of FIG. 1; and,

FIG. 5 is a longitudinal cross section view of the shoe of FIG. 1.

The dash-dot broken lines are included to show the boundaries between the claimed and unclaimed portions of the design and form no part of the claimed design.

The broken lines immediately adjacent to shaded areas represent unclaimed boundaries of the claimed design.

The remainder of the shoe shown in broken lines shows unclaimed subject matter only and forms no part of the claimed design.
